UNITED STATES PATENT OFFICE

EDWARD A. RULFS, OF NEW YORK, N. Y.

DESIGN FOR A COIN HOLDER

Application filed September 21, 1929. Serial No. 32,829. Term of patent 14 years.

To all whom it may concern:

Be it known that I, EDWARD A. RULFS, a citizen of the United States, residing at New York, in the county of New York and State of New York, have invented a new, original, and ornamental Design for a Coin Holder, of which the following is a specification, reference being had to the accompanying drawing, forming part thereof, and the holder having the same appearance on the opposite side as on the side presented.

Fig. 1 is a plan view and Fig. 2 a side elevation of a coin holder, showing my new design.

I claim:

The ornamental design for a coin holder, as shown and described.

EDWARD A. RULFS.
